Primary Examiner — Ian Simmons*Assistant Examiner* — Janice Lim(74) *Attorney, Agent, or Firm* — Parlee McLaws LLP (CGY); Sean Goodwin(57) **CLAIM**

The ornamental design for a beverage container, as shown and described.

DESCRIPTION

FIG. 1 is a front perspective view of a beverage container, showing my new design;

FIG. 2 is a front elevation view thereof;

FIG. 3 is a top plan view thereof; and,

FIG. 4 is a bottom plan view thereof.

The broken lines shown in the drawings are included for the purpose of illustrating portions of the design that forms no part of the claimed design.

1 Claim, 3 Drawing Sheets(56)
